UNITED STATES PATENT OFFICE.

WILLIAM LEFI, OF GLOVERSVILLE, NEW YORK.

GLOVE.

SPECIFICATION forming part of Letters Patent No. 759,117, dated May 3, 1904.

Application filed February 18, 1903. Serial No. 143,956. (No model.)

To all whom it may concern:

Be it known that I, WILLIAM LEFI, a citizen of the United States, and a resident of Gloversville, in the county of Fulton and State of New York, have invented new and useful Improvements in Gloves, of which the following is a full, clear, and exact description.

The invention relates to kid gloves having outside seams; and its object is to provide certain new and useful improvements in gloves, and more particularly at the joint of the thumb and body portions, whereby a very strong, durable, and well-fitting glove is produced and the strain incident to putting on the glove or when carrying packages or umbrellas, holding reins, &c., is more on the leather instead of on one portion of the seam joining the thumb to the body portion.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a plan view of the improvement. Fig. 2 is a cross-section of the same on the line 2 2 of Fig. 1. Fig. 3 is an enlarged face view of part of the blank for the hand and finger portions, and Fig. 4 is a like view of the blank for the thumb.

The blank which is formed into the body and finger portions A of the glove is of the usual shape, except the saddle-flap B, arranged at the forward wall of the thumb-opening C, and this saddle-flap B is made approximately of a pentagonal shape and integrally connected at its forward edge B' with the body portion at the forward wall of the thumb-opening C, as will be readily understood by reference to Figs. 2 and 3.

The side edges B² and B³ of the saddle-flap B extend outwardly in opposite directions, while the front edges B⁴ and B⁵ of the flap extend inward from the side edges B² and B³ to terminate in a corner B⁶, thus giving the front edge of the flap B a V-shaped appearance.

The thumb D has a closing-seam D', and its

base is provided with flaps D² and D³, joined at their inner edges D⁴ and D⁵ to the side edges B² and B³, respectively. Edges D⁶ and D⁷, extending from the flaps D² and D³ upwardly to the closing-seam D', are joined to the front edges B⁴ and B⁵ of the flap B, so that the flap B fits the portion of the hand between the thumb and the forefinger, it being understood that by the arrangement described the seams between the flaps B, D², and D³ are on opposite sides of the said connecting portion, while the corner B⁶ of the flap B joins the seam D' at the inner end thereof, as plainly indicated in Figs. 1 and 2.

Now by the arrangement described the five-cornered saddle-flap B snugly fits onto the corresponding portion of the hand to insure well fitting of the glove, and when the glove is put on and the wearer presses on the flap B to draw the thumb D into proper position then the strain incident thereto is on the leather of the flap, and hence the glove is not liable to tear at the seam connecting the thumb-piece with the body portion.

By reference to Fig. 2 it will be noticed that the seams extending from the junction of the apex B⁶ with the lower end of the seam D' extend in diverging undulating lines to the base-seam of the thumb, and hence the flap B tends to fit nicely and any inward strain on the flap is evenly distributed on the said seams and does not come on any single point, and hence the seam is not liable to break or tear.

By the arrangement described the seam connecting the thumb with the body portion does not extend beyond the base part of the thumb of the wearer, and hence when the hand is closed when carrying packages, umbrellas, or the like or on holding reins in driving such seam is not doubled up and does not come in contact with the part held, thus causing the wearer no discomfort. Furthermore, as the seam is below the bend inclosing the hand the seam is not doubled up, and hence is not liable to be injured and insures longer life of the glove.

Having thus described my invention, I claim as new and desire to secure by Letters Patent—

1. A glove having a body portion provided with an opening for the thumb, a saddle-flap

- integral on the body portion at the forward end of the opening, the said flap having side edges extending outwardly in opposite directions, and front edges extending inward from the side edges and meeting at an angle thereby forming a **V**-shaped front edge, and a thumb having a closing-seam and secured at its base to the body portion along the wall of the opening, the thumb being provided at its base with flaps secured at their inner edges to the side edges of the saddle-flap, the thumb also having edges extending from the flaps to the closing-seam and secured to the said front edges of the saddle-flap, as set forth.
- 15 2. A glove having a body portion provided with a pentagonal saddle for the hollow between the thumb and forefinger, and a thumb joined at its base part to the body portion, the base of the thumb being provided with flaps connected with the edges of the said pentagonal saddle, as set forth.
- 20 3. A glove having a body portion formed with a thumb-opening, and a saddle-flap integrally connected with the forward end of the wall of the thumb-opening, the said flap having curved side edges extending outward in

opposite directions from the junction of the flap with the body, and straight front edges extending inward from the side edges and meeting at an angle, and a thumb joined to the body portion and its saddle-flap, as set forth.

4. A glove having a body portion provided with a thumb-opening, a saddle-flap integral with the body at the said opening and having outwardly - extending side edges and a **V**- shaped front edge, and a thumb having a closing-seam and joined to the body portion and saddle-flap, the apex of the front edge of the flap being at the lower or inner end of the thumb-closing seam, the seams connecting the thumb with the saddle-flap extending in diverging undulating lines from the said apex of the flap to the base-seam of the thumb, as set forth.

In testimony whereof I have signed my name to this specification in the presence of two subscribing witnesses.

WILLIAM LEFI.
